UNITED STATES PATENT OFFICE.

EUGENE M. WESLEY, OF TACOMA, WASHINGTON.

GAME APPARATUS.

1,240,394.

Specification of Letters Patent. Patented Sept. 18, 1917.

Application filed January 15, 1917. Serial No. 142,386.

To all whom it may concern:

Be it known that I, EUGENE M. WESLEY, a citizen of the United States, residing at Tacoma, in the county of Pierce and State 5 of Washington, have invented certain new and useful Improvements in Game Apparatus, of which the following is a specification.

This invention relates to game apparatus, 10 and its object is to provide an attractive, interesting and easily understood game in which a certain amount of skill is required.

With these ends in view, the invention consists in the provision of a board having 15 a plurality of openings to accommodate hinged doors on which are representations of objects, preferably having the simulation of the cards such as utilized in a poker deck. The invention further consists in the provision 20 of novel devices for closing the doors after the same have been opened, as by means of baseballs or the like thrown by the players.

The invention still further consists in the 25 novel construction, adaptation and combination of elements, as will be hereinafter described and claimed.

In the accompanying drawings, Figure 1 is a front elevational view of a game-board 30 embodying the present invention. Fig. 2 is a rear elevation of the same, and Fig. 3 is a vertical longitudinal section thereof to an enlarged scale and shown partly broken away. Fig. 4 is a fragmentary sectional view 35 of the game-board showing the preferred means for yieldingly holding a door in closed position.

My game apparatus comprises a rectangular shaped frame formed of horizontal and 40 vertical members 5 and 6 and obliquely disposed braces 7 arranged substantially as shown in Figs. 1 and 2. Inclosed by said braces is the game-board 8 and between the respective braces and the adjacent corners 45 of the frame the spaces are occupied by panels 9 which contribute to afford rigidity to the frame. Said frame is held in upright position by the provision of supporting feet such as 10.

50 The board 8 is provided with a plurality of openings 11 arranged in series of vertical and horizontal rows. Said board about each of such holes is provided with a rabbet 12 to receive the margins of a door 13 provided 55 for the respective hole. Said doors are connected with the board from their lower ends

by means of hinges 14 to enable them to be swung rearwardly from the closed positions until arrested by encountering the horizontal rod elements 15 of a rack which is provided at the rear of the board.

As illustrated, the various rod elements are secured to upright bar elements 16. The lowermost of said rods extend through inclined ways, such as 17, in guides 18 secured to the frame or panel members of the apparatus. The rack is suspended by means of a supplementary rod 19 engaging in an arm 20 upon a horizontal shaft 21 which is journaled in boxes 22 secured to the frame. The 70 shaft 21 protrudes outside of the frame and carries a second arm 23 which, in effect, constitutes with the aforesaid arm 20, a bell-crank lever whereby the elevation of the rack may be accomplished by means of a 75 pull cord 24 connected to the arm 23.

The bell crank lever and the guideways 17 are arranged to hold the rack in substantially parallel relation with respect to the board, and when elevated by influencing the 80 bell-crank lever, the latter and said guideways direct the rack forwardly during its ascending movement. When in its normal lower position, the rack-rods are presented to receive any of the doors which may be 85 forced thereagainst in about the positions in which the doors 13¹ and 13² are represented in Fig. 3, so that they may be seen from the front through the respective door openings, as indicated by corresponding characters in Fig. 1.

When the rack is raised, moreover, the rods thereof cause any doors bearing thereagainst to be swung forwardly into closing positions, the ultimate movements of the 95 doors being effected by the momentum of the doors.

Each of the doors is provided with means to yieldingly hold the same in its closed position, such means preferably consisting of 100 a spring-pressed ball 25 (Fig. 4) provided on a door engaging in a socket 26 formed or provided therefor in the board.

The various doors have on their front faces the representation of poker playing- 105 cards, in suitable suit colors and denominations.

The apparatus is employed by one or more players each successively throwing a number of balls, as five for example, at the board, 110 endeavoring to dislodge selected doors or card representations such as will give a

"good hand," as determined by conventional poker rules.

For instance, should one of the players dislodge "three of a kind" it is obvious that he would win over a competitor obtaining no better than "two pairs."

The apparatus may also be utilized by a single player who endeavors to dislodge doors to obtain a hand, so to speak, which will exceed a predetermined value—as a pair of aces—in order to win a stake, as cigars, offered by the proprietor of the apparatus.

The invention is simple and its use is easily understood, but sufficient skill is demanded in striking predetermined card designating doors to render games played interesting and attractive, as well as sportful.

What I claim is—

1. A game apparatus comprising a board having a plurality of openings, doors provided for the respective openings and hingedly connected from their lower ends to the board; said doors having playing-card designating marks thereon, a vertically movable rack provided at the rear of the board, and means to elevate said rack to close any of the doors which may be tilted into open positions.
2. A game apparatus comprising a board having a plurality of spaced openings, doors hingedly connected to the board subjacent to the respective openings, game-designating characters marked on the respective doors, a rack, means secured to the rear of said board and having obliquely arranged ways

to guide the lower end of the rack, and means attached to the board and connected to the upper end of the rack and coöperating with the aforesaid means to effect the forward movement of the rack when the latter is elevated through the agency of the second-named means.

3. In game apparatus of the character described, the combination, with the board having openings therein, and hinged doors for said openings, of a rack, means for elevating said rack, and means connected with the rear of the board for guiding said rack forwardly to effect the closing of the doors when the rack is elevated, said guiding means also serving to cause the rack to be moved by gravity rearwardly from the board when the rack-elevating means is inoperative.

4. In game apparatus of the character described, a board having openings therein, a rabbet provided about each of said openings, doors seatable in the rabbets of the respective board openings, hinges for the doors, a rack engageable by the doors when dislodged from the respective rabbets, and means to actuate said rack for returning the doors into the rabbets for closing the respective openings.

Signed at Seattle, Washington, this 4th day of January, 1917.

EUGENE M. WESLEY.
